COMPUTING-MACHINE.

No. 895,773.

Specification of Letters Patent.

Patented Aug. 11, 1908.

Application filed September 3, 1907. Serial No. 391,034.

To all whom it may concern:

Be it known that I, ROBERT R. LANE, a citizen of the United States, residing at Detroit, county of Wayne, State of Michigan, have invented a certain new and useful Improvement in Computing-Machines, and declare the following to be a full, clear, and exact description of the same, such as will enable others skilled in the art to which it pertains to make and use the same, reference being had to the accompanying drawings, which form a part of this specification.

This invention relates to computing machines, and has for its object an attachment to that class of computing machines in which the individual numbers to be added are printed in columns on a strip of paper preparatory to imprinting on the same strip of paper the total of all the individual numbers.

The attachment consists of a holder for a piece of guard paper that covers that part of the platen upon which some of the figures would be imprinted, and thereby prevents one or more of the columns from being printed, leaving other spaces open or uncovered, in which may be imprinted any figures that may be desired, as for example in the drawings, which are attached hereto, there appears on the platen under the guard, the figure 13 in one place, and 417 opposite on the same line, put in other columns and between the two, is a space sufficient to be occupied by two columns, which on the paper would be left blank, the imprint from the type being received on the guard, (the imprint which would appear on the guard is not shown in the drawing). This might mean that document number 13, as a note, for instance, represents \$4.17, and document number 14 represents \$5.23, or clerk number 13 made a sale of \$4.17, or any other transaction in which two indicating numbers are desired, and of which a record is to be made.

In the drawings:—Figure 1, is a front view of the platen of a printing calculating machine, with the attachment in place before the platen. Fig. 2, shows a rear elevation of the attachment, detached from the platen. Fig. 3, is a section through the platen and through the attachment. Fig. 3, is taken on the section $x-x$ of Fig. 2. Fig. 4, is a section through the line $y-y$ of Fig. 2.

The attachment consists of a plate 1 supported on standards 2 and 3, which are arranged to be inserted in holes 4 and 5 in a bar of the machine, just in front of the platen.

The plate 1 is secured to the standards 2 and 3 and remains fixed in position with respect to the frame. It is provided with two inclined slits 6 and 7 through which engage the 60 necks of buttons 8 and 9, fixed to the rear face of a plate 10 that reciprocates along the inclined slots, both rising and moving side-wise. The reciprocating plate 10 is provided with fastening means for the engagement 65 therewith of a shield 11 of paper or any suitable material. An approved means of engaging the paper shield to the plate 10 is produced by cutting a slot 12 parallel with the edge of the plate 10, and near the upper edge 70 thereof. The guard 11, preferably of stiff paper, is cut of a suitable width to engage closely between the necks of the buttons 8 and 9. The upper edge of the paper is bent and thrust through the slot 12, which is considerably longer than the width of the paper shield. Apertures are cut in the paper shield to uncover those portions of the platen where it is desired to make imprints on the paper roll over the platen, and the paper shield 11 80 is left intact at places to cover those parts of the paper rolling over the platen which would be printed upon were the shield not there, and which it is desired to leave without print. On the apertures 13 in Fig. 2 provision is 85 made at the bottom of the aperture by cutting the aperture to a greater width for printing an extra figure to the left when the guard is lifted for the purpose of printing such extra figure. In normal use when it is not desired 90 to make prints in the portion where the aperture is of greater width, the plate 10 is left in its normal and lowermost position. Should it be desired to print the same, or print the extra column, in the space indicated at a in 95 Fig. 1, the plate 10 is placed with the left hand to the right. This does not shift the paper to the right, but lifts it, its motion to the right, being prevented by the buttons 8 and 9. The imprint is now made with the 100 paper in its lifted position, and the print is made, not only in the first three columns, but in the fourth column as well, in a space hitherto covered by the guard. Immediately upon releasing the left hand end of the 105 plate 10, the spring 14 retracts the plate and the paper guard is pulled downward to its first or normal position.

What I claim is:—

1. An attachment for computing machines, having in combination a platen, a guard provided with apertures, and means

22 correlating the same whereby limited relative movement of the guard with respect to the platen is permitted, substantially as described.

5 2. In an attachment for computing machines, in combination with a platen, a guard adapted to be held in protecting position thereover, a plate whereby the guard may be supported, and means for lifting and depressing the guard, substantially as described.

10 3. An attachment for computing machines, having in combination a fixed plate, a moving plate adapted to coact therewith,

being capable of motion with respect thereto only within fixed limits, an apertured guard 15 piece adapted to be supported by and to move with said moving plate and means for yieldingly opposing the movement of said moving plate from its normal position of rest with respect to the fixed plate.

20 In testimony whereof, I sign this specification in the presence of two witnesses.

ROBERT R. LANE.
